(57) **CLAIM**

The ornamental design for an onion holder for slicing as shown and described.

DESCRIPTION

FIG. 1 is a front, left and top perspective view of an onion holder for slicing, showing my new design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front, left and top perspective view of the onion holder for slicing of FIG. 1 in an environment of use; and,

FIG. 10 is an enlarged view of detail 10 in FIG. 2.

The dashed broken lines in FIG. 9 depict environmental structure and form no part of the claimed design. The dot-dash broken lines in FIGS. 2 and 10 depict the boundaries of the enlarged views and form no part of the claimed design.
